UNITED STATES PATENT OFFICE.

HENRY L. PITMAN, OF WESTFIELD, NEW JERSEY, ASSIGNOR, BY MESNE ASSIGNMENTS, TO ELLIOTT-FISHER COMPANY, OF NEW YORK, N. Y., A CORPORATION OF DELAWARE.

COMPUTING MACHINE.

Application filed April 26, 1922. Serial No. 556,661.

This invention relates to computing machines including multiplying machines, and has mainly to do with computing decimals, especially where the machine is used for making out bills.

In multiplying decimals, it frequently happens that the number of decimal places in the product is successive, and accordingly it is universal practice to disregard the figures appearing below a certain decimal place. For example, in making out bills in United States currency, anything below the cents position is disregarded. In some cases, however, it is the practice to add one cent to the product where the correct product would be half a cent or more. In some cases a cent is added where the correct product would be a third of a cent or more.

The present invention is illustrated in connection with the combined typewriting and multiplying machine of the type illustrated in the United States patent to Von Reppert, No. 1,302,250, dated April 29, 1919, in which multiplication is effected by the use of product plates. Number-bearing wheels or dial-wheels are employed to serve in registering the product in a product totalizer.

In performing some multiplications, the product will show so many decimal places as to make it necessary to provide computing units for all of them. In the illustration of the invention herein disclosed, computing units may be provided for only four decimal places; anything below the fourth decimal place being disregarded in the product and no computation taking place with respect to such low decimals. Of the computing units below the decimal point, the first may be for dimes, the second for cents, the third for mills and the fourth for tenths of mills.

In order to provide for registering an additional cent, when the mills computing unit has been actuated the required number of steps, say, for example, five steps, and thereby secure the result usual in bookkeeping, the mills computing unit is caused to carry over

one digit to the cents computing unit when the mills computing unit has been advanced five steps. The carrying operation may be similar to that illustrated in the Von Reppert patent.

In constructing the mills computing unit, there is also taken into consideration the fact that said unit may sometimes be actuated six, seven, eight or nine steps in successive operations, so that it will occasionally happen that said mills computing unit will be rotated from fifteen to eighteen steps in the aggregate during said two operations. Inasmuch as fifteen mills is equal to one and one-half cents, it is obvious that the mere provision for carrying, after the first five steps of rotation of said unit, would produce undesired results from time to time. To solve this problem, said mills computing unit is also provided with means for carrying over an additional digit onto the cents computing unit when said mills computing unit is turned fifteen steps, or, in other words, a carry-over is effected for every tenth step subsequent to the first carry-over which is effected after an actuation of five steps from normal. Therefore, said mills computing unit will carry an additional cent when it has been turned five, six, seven, eight, nine, ten, eleven, twelve, thirteen or fourteen steps, and in every such instance it will produce the desired result, and it will carry over an additional cent when it has been advanced to the fifteenth, sixteenth, seventeenth or eighteenth step, thus also securing any result desired in billing machines. It will be understood, however, that while a five and fifteen step movement is illustrated, still the invention is not limited thereto; inasmuch as it is apparent that the repeated carrying-over from the mills to the cents computing unit could occur if desired at step 1 and step 11; or at step 2 and step 12; or at step 3 and step 13; or at 6 and 16; and so on according to the desires of the user of the machines, or according to the custom which may prevail in any locality.

- In many instances it would be desirable to disregard entirely the tenths of mills denomination. Provision is made for computing in the tenths of mills place under some circumstances, because in this way the total of the bill may be increased by one or more cents in some cases, which addition would be lost without provision of mechanism to take care of tenths of mills.
- Accordingly the tenths of mills computing unit is caused, whenever it has been advanced five steps, to carry over one digit to the mills computing unit; the carrying operation being similar to that employed on the other units. This tenths of mills unit, however, is operated differently from the other computing units in the register, in that it is positively connected to its driving element and therefore returns to normal position together with said element after each actuation. Any product that belongs in a lower decimal place than the tenths of mills is disregarded and computation thereof is not performed, there being no computing units therefor.
- If desired, the tenths of mills computing unit may be set to carry over one digit to the mills computing unit when the former has been advanced one step, two steps, three steps, or any other number of steps; but it is illustrated herein as having a mill carried over when it has been advanced five steps. Occasionally this carrying-over of one digit to the mills computing unit will advance the latter from the fourteenth step to the fifteenth step, and an additional cent will be carried over on the cents computing unit, and as a consequence a cent is added frequently to the amount of the bill by reason of computing in the tenths of mills place. When the tenths of mills computing unit is advanced one step, or two, or three or four steps, nothing is carried over onto the mills place; but each time that said tenths of mills computing unit is advanced to five steps, a mill is carried over; but nothing further is carried even though the tenths of mills computing unit be advanced to six, seven, eight or nine steps. The ultimate result is but little increased by the use of the tenths of mills computing unit, inasmuch as on the average it is only about 1/18 of the time that the mills computing unit would stand either at four or fourteen at the time that a mill is carried over onto said unit; but the use of the tenths of mills unit has the effect of obtaining the ultimate number of cents more nearly correct than would be the case if the tenths of mills product were entirely disregarded as is usually done in mental computation.
- According to the invention as herein illustrated, both the mills computing unit and the tenths of mills computing unit are non-indicating. In other words, there are no dial-wheels provided for these computing units.

The operator sees only the cents, dimes and 65 dollars wheels.

Other features and advantages will herein-after appear.

In the accompanying drawings,

Figure 1 is a front elevation of a portion of 70 that part of the machine wherein the totalizers are contained.

Figure 2 is a top plan view of a portion of one of the totalizers.

Figure 3 is a sectional side elevation of one 75 of the totalizers, and shows the parts as seen from the right-hand end, the section being taken immediately in front of the cents computing unit, as indicated by the dotted line 3—3 of Figure 6.

Figure 4 is a side elevation, and shows the totalizer from its outside.

Figure 5 is a view similar to Figure 3, the section being taken on the line 5—5 of Figure 6 immediately in front of the tenths of 85 mills computing unit, and shows a carry-over rack being released.

Figure 6 is a top plan view of the totalizer, some of the parts being broken away to show the underlying structure. 90

Figure 7 is a diagrammatic side view showing the tenths of mills computing unit operated five steps to carry over one digit to the mills computing unit.

Figure 8 is a diagrammatic view showing 95 the mills computing unit operated five steps to carry over one digit to the cents computing unit.

Figure 9 is a diagrammatic view showing one of the computing units to the left of the 100 mills computing unit operated ten steps to carry over one digit to the unit of next higher order.

Figure 10 is a diagrammatic view of the mills computing unit, and shows the parts in 105 their normal positions.

Only so much of the machine illustrated in the Von Reppert patent is shown herein as is necessary to arrive at a clear understanding of this invention. The machine comprises a 110 register or totalizer section or casing 6 extending upwardly behind the typewriting machine (not shown). Said casing is provided with a front plate 7 having a sight-opening 500, through which may be observed dial-wheels 18 of an item or multiplicand register 501, and a sight-opening 502, through which the dial-wheels 245 of a product totalizer 503 may be observed. 115

The dial-wheels 18 of the item register are 120 rotatable, to display the numbers thereon at the sight-opening, by driving elements or racks operated by means controlled by the typewriter numeral-keys (not shown) while typing the multiplicand. These racks carry 125 interponents which are settable, as the dial-wheels are operated, relatively to the product plates. The product plates may be op-

erated by multiplication keys (not shown), after the interponents are set, to actuate rack connections of the product totalizer to move the racks or driving elements 152^a down-
wardly, and, under proper conditions, rotate the dial-wheels 245, of the product totalizer 503, distances equal in value to the movements of the respective racks, the amount of movement of each rack being dependent upon the 10 position of the associated interponents at that time relative to the product plates.

The dial-wheels 18 of the item register and the interponent-carrying racks are supported on a carriage 504, comprising side plates 4 and 5, to travel back and forth by means of rollers 12 on rails 13. The register carriage is effective to move one space at a time, to the left, during the typing of the item or multiplicand, to display the multiplicand at the 20 sight-opening 500. The register carriage is moved, as explained in the Von Reppert patent, to position the dial-wheels 18 denominationaly with reference to a decimal point 505 to locate the interponents denomination-
ally relatively to the computing units of the 25 product totalizer. The multiplier may now be typed. While each digit of the multiplier is typed, the sum of the partial products appears in the product totalizer, and the carriage of the item register moves one space at a time to the right to move the interponents collectively and each into co-operative relation with the connection to the computing unit of next lower order. Finally, after the 30 last digit of the multiplier is typed, the product appears at the sight-opening 502 of the product totalizer 503.

The machine may be provided with several product totalizers, only one being illustrated 10 in the drawings. Each product totalizer comprises a series of denominationaly-ar-
ranged dial-wheels 245 to indicate cents, dimes and dollars. The dial-wheels 245 may be driven by the rack-bars or driving elements 152^a through trains of gearing, each train comprising a computing wheel 231 to be rotated at the proper time by the associated rack-bar 152^a, said computing wheel driving an intermediate gear 248 meshing with a pin-
ion 246 secured to the dial-wheel 245 to rotate the latter through the proper number of steps. The computing wheels 231, intermediate gears 248 and dial-wheels 245 are mounted, respec-
tively, on rods 231^a, 248^a and 247, all of said 50 rods being supported on walls 210 of a float-
ing section of the totalizer. The floating section of the totalizer may be moved to and away from the rack-bars to move the computing wheels into or out of mesh with said bars.
60 To guide the floating section of the totalizer in these movements, there are provided links 211 and arms 212 (Figures 3, 4 and 6), the arms 212 projecting from a rock-shaft 212^a supported in walls 206 of a non-floating or
65 relatively fixed portion of the totalizer.

The totalizers are normally disconnected from the driving racks or computing bars 152^a. When a computation is to be run into the totalizer, the floating section is moved rearwardly to bring the computing wheels 70 231 into mesh with said computing bars before the latter are operated. To do this, one of the guide-arms 212 is provided with a rear-wardly-extending arm 212^x, each totalizer being provided with one of these arms, and the various arms being operable by an upward movement of a common operating bar or plate 214, each arm engaging between two pins 213 and 215 on said bar. This movement brings the computing wheels 231 into engagement 80 with the computing bars 152^a, after which the computing bars may be operated to rotate the dial-wheels 245. After the computing bars 152^a have been operated, the swinging section of the totalizer is released, thus dis-
engaging the computing wheels from the computing bars and allowing the latter to be restored to their normal positions in a manner clearly described in the above-named Von Reppert patent. 90

Carry-over devices are provided between the computing units to carry one digit to the computing unit of next higher denominational order when a computing unit passes through zero. Each carry-over device comprises a carry-over wheel or disk 232 secured to the computing wheel 231 and on the side towards the one of next higher denominational order. There are three cams or teeth 233 provided on each carry-over wheel, one at 95 every tenth step thereof, the computing wheel 231 making one-third of a revolution to a complete revolution of the dial-wheel 245. When a dial-wheel passes through zero, one of the carry-over teeth 233 engages a carry-
over pawl 234 to rock it about a fulcrum-rod 235, upon which all of the carry-over pawls are supported, to withdraw a stud 239, carried by an upwardly-extending arm 234^x of said pawl, from beneath a shoulder 240 of a 100 carry-over rack 237, from the Figure 3 po-
sition to the Figure 9 position. A spring 236, connected between the pawl and said rack, immediately becomes effective to pull the carry-over rack downwardly to the Figure 115 9 position a distance equal in value to one digit, or, in other words, one step. The as-
sociated rack of each carry-over pawl is ar-
ranged so that it may engage the computing wheel 231 of next higher order, and, as soon 110 as the floating section of the totalizer is swung back to normal position to disengage the computing bars 152^a, the computing wheels 231 are brought into mesh with the carry-over racks 237. A universal bar 256 is 120 operated to move all of the released carry-
over racks 237 back to their normal positions, thus advancing the associated computing wheels one step, which is transferred to the 125 dial-wheels 245. Upon the return of the 130

carry-over pawls, the studs 239 snap under the shoulders 240 to hold said racks in their normal positions. The carry-over racks are supported in the non-floating portion of the 5 totalizer and are guided on rods or bars 238^a and 238^b.

Each totalizer may occupy a neutral or ineffective position and may be moved to the right or left to connect it for computation or 10 clearing. When the totalizer occupies a neutral position, its actuating arm 212^x lies over a slot 506 in the stud 213 on the actuating bar 214 (Figure 3). Consequently, when the latter is operated, the arm 212^x enters the slot 15 506, and, as a result, the totalizer remains disconnected from the computing bars.

To set the totalizer to multiply, there is provided a rock shaft 203, which may be operated in a clockwise direction in Figure 1, 20 by means of a finger-piece 202, to set a pointer 209, secured to said shaft, opposite the sign "Mult." from the neutral sign "N". The shaft 203 has secured thereto an eccentrically mounted stud 204 at its rear end (Figure 6), 25 which projects into a slot 507 of a lateral extension or bar 205 on the right-hand end-plate 206 of the totalizer, so that, as the shaft is rotated in a clockwise direction, the totalizer is moved toward the right to bring the 30 computing gear-wheels 231 into effective relation with the computing rack-bars 152^a (see Figure 2). As the totalizer is moved rightwardly, the actuating arm is moved from above the slot 506 in the stud 213 of the actuating bar 214, so that, when the latter is 35 operated, the swinging section of the totalizer is moved rearwardly to connect the computing wheels 231 with the computing bars 152^a.

When it is desired to clear the totalizer, or, 40 in other words, bring the dial-wheels back to zero, it may be moved in the opposite direction by rotating the finger-piece in a counterclockwise direction until the pointer is 45 opposite the sign "Clear" (Figure 1). By this movement of the totalizer, the computing wheels are brought into effective relation with a set of rack-bars 152^b (Figure 2) arranged alternately between the computing 50 rack-bars 152^a. Each rack-bar 152^b is geared to the computing rack-bar 152^a of the associated computing unit to be actuated thereby an equal amount but in the opposite direction. After the totalizer has been set to its "clear" 55 position, a "clear" key (not shown) may be operated, which causes the "clear" rack-bars 152^b, through the medium of the computing bars 152^a, to rotate the computing wheels 231 in counterclockwise directions. Each computing wheel is arrested at "0" by one of the teeth 233 which strikes against the flat face of the carry-over pawl 234, yielding connections being used, as shown in the Von Reppert patent, between the operating mecha- 60

nism and the computing rack-bars, to allow 65 the carry-over wheels to be arrested sooner or later without stopping the actuating mechanism.

The machine thus far described may be like that shown in the patent to Von Reppert, and 70 is capable of computing as low as the cents position only. The present invention, however, provides means whereby computation may be performed below the cents position, as, for example, in the mills and tenths of 75 mills positions. For this purpose, there are provided computing units for the last two named positions.

In the present invention, a digit is automatically carried over to the cents computing 80 unit when the mills computing unit is actuated through five steps from normal position; in other words, if five mills are run in, one cent is carried over to the cents computing unit. If the mills computing unit is actuated ten steps subsequent to the first carry-over, another cent is carried over. Thus, if the mills computing unit is moved fifteen steps from normal position, two cents are carried over to the cents computing unit. To 90 this end, the mills computing wheel 231 normally occupies a position with the nearest tooth 233 of the carry-over wheel 232 five steps away from a tooth 600 on a carry-over pawl 601 associated with the mills computing 95 unit. Consequently, the carry-over pawl 601 is operated by the tooth 233 when the mills computing wheel is operated through five steps, to release the carry-over rack associated with the cents computing wheel 231, as 100 shown in Figure 8, the cent being carried over when the rack 237 is restored to normal, in the manner previously described.

The mills computing wheel may be restored to normal position by reversely rotating it in a way similar to that described for the other computing wheels when they are returned to "0". To arrest the mills computing wheel in its proper position, there is mounted a stop 602 on the carry-over pawl 110 601 five steps away from the carry-over tooth 600. Both the carry-over tooth 600 and the the stopping tooth 602 are pivotally mounted, so that said carry-over tooth and said stopping tooth may readily be brushed out of the 115 way by the teeth 233 of the carry-over wheel 232, against the tension of suitable springs 603 and 604 in order to pass by without operating the pawl 601. Thus when the 120 carry-over wheel 232 is rotated in an ineffective or counterclockwise direction (Figure 10), the tooth 600 is brushed aside about its pivot, when the carry-over wheel is rotated in a clockwise direction the stop tooth 602 is brushed aside thereby about its pivot 125 in a counterclockwise direction.

The tenths of mills computing unit does not have a computing wheel as the other com-

puting units, but instead there is employed a computing lever 605 pivoted on the rod 231^a which supports the computing wheels 231. The lever 605 is connected to a tenths of mills 5 computing bar 606 by a link 607. Said computing bar may be like the bars 152^a except that it is not provided with rack-teeth. It may be actuated in a similar way by means including a link 608 (Figure 4). The computing lever reciprocates back and forth with the computing bar 606 and carries a one-way acting pawl 609, which, when the computing lever is swung in a clockwise direction, engages one of the carry-over pawls 234 to release the carry-over rack 237 associated with the mills computing wheel (Figure 7). The release of said rack is effected, however, only when the tenths of mills computing bar 606 is moved through five or more steps, the computing lever 605 moving idly when actuated less than five steps, and returning with the computing bar after each actuation to normal position, as shown in Figure 5, where the pawl 609 is five steps away from the 15 carry-over pawl. A contractile spring 610 is connected between the computing lever and the pawl 609 to hold the pawl against the shaft which arrests it in its normal or effective position relatively to the computing lever. This spring allows the pawl 609 to 25 pass the carry-over pawl 235 more readily on its return. The digit is finally carried over into the mills computing unit on the return stroke of the carry-over racks, as hereinbefore described.

It is preferable to effect the carry-over from the tenths of mills computing unit to the mills computing unit at the fifth step of the tenths of mills computing bar 606. The 40 carry-over may be effected, however, sooner or later by connecting the link 607 at different positions on the computing bar 606, there being several holes 611 in said bar for this purpose. In this way carry-over may be effected at three, four, five, six or seven step movements of the computing bar, according to the connection of link 607 with the computing bar 606.

To further illustrate the operation of the 50 invention, let it be assumed that the following computation is to be performed:

562 lbs. @ 9 1/4 cents (.0925) per lb.

The "562" is set up in the item register. The 55 operative then sets the item register denominational relatively to the product totalizer, as pointed out in the above-named Von Reppert patent, page 16, line 119, to line 18 of page 17, and proceeds to type the ".0925". While this is being done, the item register carriage 504 steps to the right automatically one space at a time after the typing of each digit of the multiplier so as to position the computing units of the item register properly with respect to the computing units of

the product register. Finally, the product of 562 times .0925, which equals 51.985, is computed in the product totalizer.

As the computation progresses, the numbers show in the item register and the product totalizer in the following order:

	Item register	Product totalizer	
After item (562) is typed... The item-register-carriage is then automatically advanced two spaces as the typewriter carriage is tabulated to the multiplicand position, and the item register then shows.....	5.62	00000.00	75
The "0" of the multiplicand is then typed and the item-register carriage steps down one step.....	562.00	00000.00	80
After typing the "9".....	56.20 5.62	00000.00 50.58 +1.124 +. 5	1st partial product. 2nd partial product. Amount on mills computing unit when in normal position.
After typing the "2".....	.56	51.709 +.281	3rd partial product.
After typing the "5".....	.5	51.99	Final product.

The mills computing unit is non-indicating; consequently, the values in the mills denominational position of the product totalizer are represented in dotted lines in the above illustration.

It will be understood that at any time the tenths of mills computing unit of the product totalizer stands at "4", as in ".984", and a half mill (.0005) is run into said tenths of mills computing unit, one cent is carried over to the cents computing unit; thus, in this illustration, the totalizer would indicate ".94".

From the foregoing, it will be understood that all the computing units of the product totalizer, above and including the cents computing unit, are provided with dial-wheels and are therefore visible or indicating computing units. The mills and tenths of mills computing units are not provided with dial-wheels, and are, therefore, non-indicating or blind computing units. It will further be understood that all of the computing units above and including the mills computing unit are accumulative, or, in other words, the numbers, as they are run in, are added to those already in said units, but the tenths of mills computing unit is a non-accumulative reciprocative computing unit, since it is restored to normal position after each number is run in. Further it will be understood that the register is provided with a sight-opening, that the computing units are arranged in regular denominational order from left to right, and that the result of the computation is displayed at the sight-opening by the visible computing units only. Thus, there is provided a totalizer which is capable of computing to the fourth decimal place and which indicates only to the second decimal place or

cents position, and whether the computation of a fraction of a cent is or is not to effect a carry-over of a cent is determined automatically, in other words without attention of the operative.

Variations may be resorted to within the scope of the invention, and portions of the improvements may be used without others.

Having thus described my invention, I 10 claim:

1. In a computing machine, having a plurality of accumulating computing units arranged in denominational order, and carry-over mechanism for each unit to carry one 15 digit at every tenth step thereof to the computing unit of next higher order, the combination of a non-accumulating computing unit adjacent to and below the accumulating computing unit of lowest order, said non-accumulating computing unit comprising means to carry one digit to the accumulating computing unit of lowest order when the non-accumulating computing unit is actuated through less than ten steps.
2. In a computing machine, having a plurality of indicating computing units arranged in denominational order, and carry-over mechanism for each unit to carry one digit at 20 every tenth step thereof to the computing unit of next higher order, the combination of two non-indicating computing units arranged in denominational order adjacent to and below the indicating computing units, all the computing units except the one of lowest order being accumulative, the last-named unit comprising means operative when actuated through less than ten steps to effect a carry-over of one digit to the accumulative computing unit of lowest order, and carry-over 25 mechanism to effect a carry over of one digit, when the accumulative unit of lowest order is actuated over a definite number of steps less than ten, to the indicating computing unit of lowest order.
3. In a computing machine having a plurality of accumulative computing units arranged in denominational order, and carry-over mechanism for each unit to carry one digit at every tenth position over to the computing unit of next higher order, the combination of a non-accumulative computing unit arranged adjacent to and below the accumulative computing units, the non-accumulative computing unit being effective when 30 actuated through five steps from normal position to carry one digit to the accumulative unit of lowest order, the carry-over mechanism associated with the accumulative unit of lowest order being effective, when the latter is moved through five steps from normal position, to cause a carry over of one digit to the computing unit of next higher order and to carry over one digit for each subsequent movement of ten steps of said accumulative unit of lowest order.
4. In a computing machine having a plurality of computing units arranged in denominational order, the combination with carry-over devices associated with all of said units except the one of lowest order to carry 70 one digit to the computing unit of next higher order when a computing unit is actuated over ten steps, of a carry-over device to carry one digit to the computing unit of second lowest order when the computing unit of lowest order is actuated over a definite number of steps less than ten, all of said units except the one of lowest order being accumulative, and the computing unit of second lowest order being effective to carry one digit to the unit of 75 next higher order when moved a definite number of steps less than ten from its normal position, said unit of second lowest order being also effective to subsequently carry over a digit at every tenth step.
5. In a computing machine, the combination of a first computing unit and a second computing unit arranged, respectively, in ascending denominational order, said units including individual actuating elements operable over predetermined variable distances, devices operable by said actuating elements, the device of the first unit returning to normal after each operation of the associated actuating element, the device of the second 80 unit being accumulative and remaining in position after each operation by the associated actuating element, and means operable by the device of the first unit when said device is actuated beyond a definite number of 85 steps to cause the device of the second unit to be advanced one step independently of its associated actuating element.
6. In a computing machine, the combination of a first computing unit and a second 90 computing unit arranged, respectively, in ascending denominational order, said units including individual actuating elements operable over predetermined variable distances, the first computing unit including a lever 95 operable by the associated actuating element, said lever returning to normal after each operation of the associated actuating element, the second unit including a computing wheel, said wheel remaining in position after each 100 operation by the associated actuating element, and means operable by the computing lever when it is actuated beyond five steps to cause the computing wheel to be advanced 105 one step independently of its associated actuating element.
7. In a computing machine, the combination of an accumulating computing unit, a non-accumulating computing unit, said units being arranged, respectively, in descending 110 denominational order, the non-accumulating unit being completely restored to normal position after each operation, and means actuated by the non-accumulating computing unit 115 when operated a definite number of steps less 120

than ten to cause one digit to be carried to the other computing unit.

8. In a computing machine, the combination of a mills computing unit, a tenths of mills computing unit, actuating elements for said units, the tenths of mills unit being connected to be completely restored to normal position after each actuation, and means actuatable by the tenths of mills computing unit when it is operated a definite number of steps less than ten to cause one digit to be carried to the mills computing unit.

9. In a computing machine, the combination of a tenths of mills computing unit, a mills computing unit, said units being arranged in denominational order, actuating elements for said units, the tenths of mills unit being completely restored to normal position after each actuation, means actuatable by the tenths of mills computing unit when operated five steps to cause one digit to be carried over to the mills computing unit, a cents computing unit, and means actuatable by the mills computing unit when the latter is operated five steps to cause one digit to be carried to the cents computing unit, said last-named means being operable at every tenth step, after the first carry over is effected, to carry one digit to the cents computing unit.

10. In a computing machine, the combination of accumulating computing units, a non-accumulating computing unit, carry-over devices, means to actuate said computing units, said means including a bar associated with the non-accumulating computing unit, one of the carry-over devices being associated with the non-accumulating computing unit, and adjustable means associated with the non-accumulating computing unit to effect a carry-over at a predetermined number of steps less than ten of the non-accumulating computing unit.

11. In a computing machine, the combination of accumulating computing units, a reciprocating computing unit, carry-over devices, means to actuate said computing units, said means including a bar associated with the reciprocating computing unit, one of the carry-over devices being associated with the reciprocating computing unit, adjustable means associated with the reciprocating computing unit to effect a carry-over at a predetermined number of steps less than ten of the reciprocating computing unit, said adjustable means including a link, and means for variably connecting said link with said computing bar.

12. In a computing machine, the combination of a register including a computing unit, a carry-over device, and means between said computing unit and said carry-over device to render the latter effective when the computing unit is moved a predetermined distance in one direction and operable to enable the computing unit to be restored without ren-

dering the carry-over device effective, when actuated a fraction of the predetermined distance, said computing unit including a pivoted lever and a pivoted spring-pressed one-way pawl carried by said lever.

13. In a computing machine having reciprocatable computing racks and accumulating register-wheels actuated thereby for computing in dollars and cents, and carry-over mechanism for the register-wheels, the combination of a non-registering mills computing wheels operable by a reciprocatable computing rack of carry-over mechanism for the mills-wheel to carry a fractional value as one cent to the cent-registering wheel, and a tenths of mills computing device including a reciprocating trip-carrying computing lever operable by a reciprocatable computing bar and conditioned to effect a carry-over movement of predetermined extent to the mills computing wheel.

14. In a computing machine having reciprocatable computing racks and accumulating register-wheels actuated thereby for computing in dollars and cents, and carry-over mechanism for the register-wheels, the combination with a non-registering mills computing wheel operable by a reciprocatable computing rack, of carry-over mechanism therefor to carry a fractional value as one cent to the cent-registering wheel, a tenths of mills computing device including a reciprocating trip-carrying lever operable to trip and condition the carry-over mechanism to the mills computing wheel, a reciprocatable tenths of mills computing bar, and a link adjustably connecting said computing bar with the tenths of mills computing device and operable to predetermine the normal position of the mills computing device and determine the extent of the carrying movement.

15. In a computing machine having reciprocatable computing racks and accumulating register-wheels actuated thereby for computing in dollars and cents, and carry-over mechanism for the register-wheels, the combination with a non-registering mills computing wheel operable by a reciprocatable computing rack, of carry-over mechanism for the mills-wheel operable to effect a carry-over movement of five mills to the cent-wheel, and a non-registering tenths of mills computing device operable by a reciprocatable computing bar and conditioned to effect a carry-over movement to the mills-wheel of less than ten steps, from a predetermined normal position.

16. In a computing machine having reciprocatable computing racks and accumulating register-wheels actuated thereby for computing in dollars and cents, and carry-over mechanism for each register-wheel, the combination with a mills computing wheel operable by a reciprocatable rack-bar, of mills carry-over mechanism including a carrier having a pair of pawls, and means carried by

the mills-wheel and rotatable in one direction to engage one pawl for a normal or zero setting position for said wheel, and rotatable in the opposite direction to trip the other pawl and effect a carry-over movement to the next higher wheel of predetermined carry-over extent.

17. In a computing machine having reciprocatable computing racks and accumulat-
10 ing register-wheels actuated thereby for computing in dollars and cents, and carry-over mechanism for each register-wheel, the combination with a mills computing wheel operable by a reciprocatable rack-bar, of a mills

carry-over mechanism including a carrier 15 having a pair of pawls, and a plurality of carrying teeth rotatable with the mills computing wheel in either direction, each tooth operable to engage with one pawl on the carrier for a normal or zero setting position 20 during the rotation of the mills-wheel in one direction, and each tooth operative when said wheel is rotated in the reverse direction, to trip the other pawl and effect successive carry-over movements to the cents-wheel 25 when actuated for not less than five mills.

HENRY L. PITMAN.
